UNITED STATES PATENT OFFICE.

RICHARD BROOKE DORMAN, OF MIDDLESBOROUGH, ENGLAND.

SUPERHEATER FOR LOCOMOTIVE, MARINE, AND OTHER BOILERS.

1,372,491.

Specification of Letters Patent. Patented Mar. 22, 1921.

Application filed March 25, 1920. Serial No. 368,628.

To all whom it may concern:

Be it known that I, RICHARD BROOKE DORMAN, a subject of His Majesty the King of England, and resident of Middlesbrough, in the county of York, Kingdom of England, have invented certain new and useful Improvements in or Relating to Superheaters for Locomotive, Marine and other Boilers, of which the following is a

specification.

This invention relates to superheaters for locomotive, marine and other boilers and has for its object to provide improved means for use in connecting the ends of the superheater tubes to the header box hereinafter referred to as header, the said means forming a simple attachment for the purpose and one which is easy of access when it is desired to tighten up the joints, or slacken them for the purpose of taking out the superheater tubes from the boiler flue tubes.

According to the present invention the improved means comprises a flange or connecting piece provided with a recess, slot, groove or channel extending from one side of the flange or connecting piece hereinafter referred to as flange, to the other side in a direction parallel to the face of the header to which the superheater tubes are to be secured. The direction of the recess, slot, groove or channel in the flange when in position is always at right angles to the direction of the shanks of the connecting or securing bolts. The arrangement is such that the nuts or other means used for tightening up the superheater tube joints bear on the face of the header box opposite to the face to which the superheater tubes are attached. It is obvious that in this position the nuts or other tightening means are most accessible. The recess, slot, groove or channel in the flange may be of any suitable shape and is in all cases undercut to receive the head of the securing bolt. The above description refers to the connection of a single superheater element or unit to its header but any number of such elements or units may be employed all connected to the header or headers by a recessed, slotted, grooved or channeled flange as hereinbefore described. The securing bolts are preferably T-bolts the heads of which lie in the

respective undercut recesses, slots, grooves or channels in the flanges.

The adjacent ends of the bolt heads are arranged to butt one against the other so as to keep the bolt heads always in position to receive the flanges when placing the superheater elements or units in position in the flue tubes, joint or packing rings being used to obtain a steam tight joint.

The header may be of any suitable design and is preferably provided with a projecting rib or fin to act as a stop when placing the top row of superheater elements or units in position in the boiler. The said rib or fin extends across the header and also acts to prevent the recesses, slots, grooves or channels in the flanges being choked by the small ashes coming through the flue tubes.

Two types of flanges may be employed, which may be described as the fixed type and the loose type, the fixed type of flange having two or more holes to receive the corresponding tube ends. The outer end of each hole is preferably formed as a clearing hole, the tube end being expanded to fit tightly against the inner part of the hole. In the loose type of flange the holes therein to receive the tube ends are clearing holes, the tube ends being expanded to fit lightly into holes in washers or collars interposed between the flanges and the packing or joint rings against the adjacent face of the header.

The bolt heads may be of any suitable form in cross section such as cylindrical, oval or elliptical or rectangular and are provided with means to prevent rotation of the bolts in the recess, slot, groove or channel in the flange, when tightening or slackening the nuts thereon.

I will describe with reference to the accompanying drawing a construction in accordance with the present invention as applied to a locomotive boiler from which its general application will be readily understood, but I do not limit myself to the precise construction described and illustrated.

Figure 1 is a vertical section of a header showing the connection of a plurality of superheater elements or units in accordance with the present invention.

Fig. 2 is a section on the line A, B, Fig. 1.

Fig. 3 shows a cross section of a modified form of connection also in accordance with the present invention.

Fig. 4 is a plan of the flange shown in Fig. 3.

Figs. 5, 6, 7, 8 and 9 are detail views hereinafter described.

Referring to Figs. 1 and 2 of the drawings, 1 is the smoke box tube plate of a locomotive boiler, 2 the main steam pipe from the regulator valve in the dome, and 3 is one of the flue tubes in which a superheater element 4 is disposed. 5 is the header-box which may be of any suitable design. A rib or fin 6 may be provided to act as a stop when placing the top row of elements in position in the boiler. The rib or fin 6 which extends across the header box 5 also prevents the slots 7 in the flanges 8 from becoming choked by small ashes coming through the flue-tubes. The flanges for securing the superheater tube ends are indicated at 8, each flange being provided with an undercut slot or channel 10. The slot or channel 10 is engaged by a bolt head 11, the joint being tightened up by securing bolts 12 and nuts 13. The bolt heads 11 are provided with faces 14 which butt one against the other so as to keep the bolt heads 11 always in position to receive the flanges 8 when placing the superheater elements 4 in the flue tubes 3. Joint or packing rings 15 are used to make a steam tight joint.

Fig. 2 shows the improved attachment with a flange 8 into which the superheater tube ends are expanded as at 16.

In Fig. 3 a loose flange type of connection is shown, the tube ends passing loosely through the holes 17 in the flange 8 and being expanded into collars 18.

The bolt heads 11 may be of different design and may be provided with projections 20 to prevent rotation of the bolts in the flange slot 10 when tightening or slackening back the nuts.

In Figs. 1, 2 and 9 the bolt heads 11 are shown as of cylindrical cross section and elliptical longitudinal section or the ends of the bolts may be rounded off as shown, the bolts being circular in cross section with or without flattened sides as shown at 21. In Figs. 4, 5 and 6 the bolt heads are shown as being of approximately elliptical cross section and circular in plan, the bolt near the junction with the head being of oval section as at 22 with or without flattened side parts 23, 24.

The improved attachment hereinbefore described may be used with any design of header and in view of the accessibility of the securing nuts is most suitable for the attachment of marine fire tube superheater elements to the header boxes.

The device may also be applied to almost any form of tube joints with advantage.

What I claim as my invention is:—

1. In a device of the class described, the combination of a header, a tubular superheater element and means securing the ends of the elements to the header comprising a flange or connecting piece provided with an undercut slot, and a bolt, the head of which lies in the slot, the longitudinal dimension of the slot in the flange when in position being always at right angles to the axis of the shank of the connecting bolt.

2. In a device of the class described, the combination of a header provided with an opening extending through it, a tubular superheater element, and means securing the ends of the element to the header comprising a flange or connecting piece provided with an undercut slot, the longitudinal dimension of the slot in the flange when in position being always at right angles to the axis of the shank of the connecting bolt, a bolt, the head of which lies in the slot and which extends through the opening in the header and a nut engaging the end of the bolt.

3. In a device of the class described, the combination of a header provided with an opening extending between two of its faces, a tubular superheater element, and means securing the ends of the element to one of the said faces of the header comprising a flange or connecting piece provided with an undercut slot, a bolt the head of which lies in the slot and which extends through the opening of the header, the longitudinal dimension of the slot in said flange when in position being always at right angles to the axis of the shank of the connecting bolt, and a nut engaging the end of the bolt, and exerting pressure against the adjacent face and drawing the flange toward the opposite face of the header, the engaging faces of the head and undercut slot permitting a slight relative rocking movement.

4. In a device of the class described, the combination of a plurality of aligned flanges each provided with an undercut slot in one face, the slots all being in alignment, two openings extending through each flange on opposite sides of the slot, a superheater element end entering each opening from the side opposite the slot, a header adjacent to the slotted sides of the flanges with an opening through it opposite the slots, bolts extending through said last named opening, the head of one bolt lying in each slot, the longitudinal dimension of the slots in the flanges when in position being always at right angles to the axis of the shanks of the connecting bolts, and a nut on the opposite end of each bolt exerting pressure against the header, thereby drawing the flange toward the header.

5. In a device of the class described, the combination of a plurality of aligned flanges each provided with an undercut slot in one

face, the slots all being in alinement, two openings extending through each flange on opposite sides of the slot, a superheater element end associated with each opening, entering it from the side opposite the slot, a header adjacent to the slotted sides of the flanges with an opening through it opposite the flanges, a plurality of alined bolts extending through said last named opening, 10 each slot having in it the head of one bolt, adjacent heads abutting against each other, the longitudinal dimension of the slots in the flanges when in position being always at right angles to the axis of the shanks of the connecting bolts, and a nut on the opposite end of each bolt exerting pressure against the header, whereby when the nuts are drawn up the flanges are drawn toward the header and when the nuts are loosened up the flanges may be slipped off or on the 15 heads, the bolt heads retaining each other in alinement.

In testimony whereof I have hereunto signed my name.

RICHARD BROOKE DORMAN.
